UNITED STATES PATENT OFFICE.

CARL NEILSEN, OF DETROIT, MICHIGAN.

DESIGN FOR A VEHICLE-SIGNAL HOUSING.

Application filed December 4, 1924. Serial No. 11,582. Term of patent 3½ years.

To all whom it may concern:

Be it known that I, CARL NEILSEN, a subject of the King of Denmark, and who has declared his intention of becoming a citizen of the United States, and who is residing at Detroit, in the county of Wayne and State of Michigan, have invented a new, original, and ornamental Design for Vehicle Signal Housings, of which the following is a specification, reference being had to the accompanying drawings, forming part hereof.

Fig. 1 is a top plan view of a vehicle signal housing showing my new design.

Fig. 2 is a front elevational view of the same.

I claim:

The ornamental design for a vehicle signal housing, as shown.

In testimony whereof, I have signed the foregoing specification.

CARL NEILSEN.
